Primary Examiner—Alan P. Douglas**Assistant Examiner—Jeffry H. Musgrove****Attorney, Agent, or Firm—Palmatier, Sjoquist & Helget****[57]****CLAIM**

The ornamental design for a sign holder clamp with offset support, as shown and described.

DESCRIPTION

FIG. 1 is a bottom plan view of the invention;

FIG. 2 is a top plan view of the invention;

FIG. 3 is a left side elevational view of the invention;

FIG. 4 is a right side elevational view of the invention;

FIG. 5 is a front elevational view of the invention; and,

FIG. 6 is a rear elevational view of the invention.

Fig. 1.

Fig. 2.

Fig. 3.

Fig. 4.

Fig. 5.

Fig. 6.
